[57] ABSTRACT

Prefabricated concrete structures are raised and lowered to receive transport vehicles by jacks mounted in the corners of their floors. The lower end of each jack cylinder (11) is coarsely threaded cylindrical member (22) having a smooth guide surface (19) above the threads (18) and an outwardly flaring conical surface (21) above the smooth surface. An anchor plate (14) is embedded in a hole (12) in the concrete floor (13) contoured to mate with and receive the cylindrical member. The anchor plate has a central hole (15) surrounded by an offset split ring (16) to define a single turn thread.

FLOOR JACK ANCHORING ARRANGEMENT FOR GARAGE LIFTS

BACKGROUND OF THE INVENTION

1. Field of the Invention

This invention relates to an apparatus for raising and lowering roomsized building units, particularly prefabricated garages made from reinforced concrete, with the aid of jacks anchored in openings in the floor of the building by means of fittings which surround the openings and which are concreted into the floor, by turning the jacks.

2. Description of the Prior Art

Reinforced concrete garages prefabricated in the factory are conventionally delivered to the place of installation by special transporting vehicles. Apparatuses for raising and lowering the garages are known for loading and unloading these vehicles. At the place of manufacture the garage is raised in such a way that the transporting vehicle with the loading appliance or a trailer can wholly or partly be driven underneath the garage.

The invention is based on a known apparatus for raising and lowering prefabricated garages, whereby at least three through openings are provided in the garage floor. In the garage in the vicinity of these openings hydraulic jacks are installed, whose rams are extended downwards through these openings and raise the garage by bracing on the subsoil.

The problem of the invention is to further develop and improve lifting equipment of this type for prefabricated garages and the like. In particular, as compared with known constructions, expenditure on wasted material and erecting the jacks to be reduced.

SUMMARY OF THE INVENTION

According to the invention this problem is solved by an apparatus in which the fitting fitted in the garage floor projects into the openings with projections which are substantially in one plane, whereby in an area adjacent to the fitting counter-projections are provided on the jack for anchoring to the projections of the fitting.

Therefore an important feature of the invention is the construction of the lost fitting fixed in the garage floor which in this case is constructed as a single anchor plate with a hole surrounding the jack. The ring in the hole has a screw thread-like configuration and engages in an outer coarse pitch thread on the jack. The anchor plate is constructed in a single operation by stamping and shaping the ring in the hole to form a screw thread.

According to a further feature of the invention, in addition to the anchoring in the lower area of the garage floor cross-section by the anchor plate engaging in the jack thread, a jack guide is provided in the opening of the garage floor to prevent lateral movement. Therefore, above the relatively short thread the jack has a cylindrical guide which is form-locked in the corresponding opening in the garage floor. Whereas the anchor plate can mainly take up vertical forces, the cylindrical guide can transfer lateral forces and bending moments.

Furthermore the jack is provided with a preferably conical extension which engages in a corresponding counter-surface of the garage floor, particularly in the opening thereof. Due to the action of the thread in conjunction with the anchor plate on turning the jack, it is drawn into the opening in the garage floor until the conical contact surface of the jack engages with a cer-

tain tension on the conical counter-surface of the garage floor.

BRIEF DESCRIPTION OF THE DRAWINGS

5 In the drawings:

FIG. 1 shows a lifting apparatus according to the invention in the mounted state with part of a garage in vertical section,

10 FIG. 2 shows a detail of the apparatus of FIG. 1 in side view,

FIG. 3 shows the fitting for mounting in the garage floor, as a detail in side view,

15 FIG. 4 shows a ground plan of FIG. 3, and

FIG. 5 shows one corner of a concrete garage during the manufacture thereof.

DESCRIPTION OF THE PREFERRED EMBODIMENT

Referring now to the drawings, jacks 10 comprising a 20 hydraulic cylinder 11 and a downwardly extendable piston 10a movable therein are used for raising and lowering prefabricated garages of reinforced concrete.

The floor 13 of the garage is provided with four openings 12 in the corners thereof. The jacks 10 are 25 mounted and anchored in the openings 12, so that the garage forces are transferred to the jacks 10. In the represented embodiment jack 10 is fitted solely in the floor 13 of the garage.

To this end a fitting in the form of an anchor plate 14 30 is concreted into the floor 13. This anchor plate 14 is located in the lower cross-sectional area of floor 13. It is provided with a preferably central hole 15 which when the anchor plate 14 is mounted surrounds opening 12. A circular ring 16 of anchor plate 14 surrounding hole 15 passes laterally into opening 12.

35 By appropriate shaping, ring 16 is constructed as a screw thread. For this purpose anchor plate 14 has a radial slot 17 extending over the width of the shaped ring 16. On both sides of radial slot 17 ring 16 is bent 40 to opposite sides in such a way that screw thread is formed on both sides of the central plate of anchor plate 14. The anchor plate 14 is preferably made in one operation by simultaneous stamping and shaping.

The lower end of jack 10 is provided externally with 45 shaped parts permitting form-locking with anchor plate 14 by turning jack 10. In the represented preferred embodiment at the lower end of jack 10 is provided a coarse pitch thread 18 in which engages the screw thread-like ring 16 of anchor plate 14 by turning jack 10 in opening 12. The coarse pitch thread 18 is relatively short, consisting of somewhat less than two turns. If the jack 10 is turned by at least 360° it is sufficient to ensure a stable connection between thread 18 and anchor plate 14. In this case the thread is a trapezoidal 55 thread.

Outside and above thread 18, jack 10 is constructed with a cylindrical guide 19 which fits into the cylindrical opening 12 of floor 13. Guide 19 and the relevant portion of opening 12 insure the lateral guidance of 60 jack 10.

Above guide 19, jack 10 is also provided with a cone 20 which fits into a conical extension 21 of opening 12 in the area of the latter towards the inside of the garage. At the same time the conical extension 21 facilitates 65 the insertion of the lower end of jack 10 into opening 12.

Preferably the dimensions of cone 20, conical extension 21, thread 18 and anchor plate 14 are so matched

to one another that on inserting jack 10 into anchor plate 14 the outer surface of the cone 20 is pressed against the inner surface of conical extension 21. Therefore the lower end of the jack rests under a certain tension in opening 12.

Thread 18, guide 19 and cone 20 form part of an anchoring member 22 detachably arranged on jack 10 as a separate member, particularly by means of thread 23.

The problem of manufacturing the opening 12 with concreted-in anchor plate 14 is also solved in a special manner according in the invention. As the formwork member for forming opening 12 is provided a core member 24 of elastic material, particularly plastic which before concreting is placed in a formwork 25. Core member 24 is detachably anchored on a base portion 27 of the formwork with a centrally inserted tie bolt 26 or the like. Core member 24 is constructed in the same way as the anchor member 22, i.e. it is also provided with outer thread 18, onto which is screwed anchor plate 14 before assembling core member 24 in formwork 25. Core member 24 with the mounted anchor plate 14 is then inserted and concreted into formwork 25. After the concrete has set core member 24 is removed from the floor 13 of the garage. Anchor plate 14 is left behind at the desired point in the floor 13. In the lower area an appropriate internal thread is embedded in the concrete.

What is claimed is:

1. In an apparatus for raising and lowering a room-sized building unit, particularly a prefabricated garage made from reinforced concrete, with jacks anchored in openings in the floor of the unit, the improvement comprising:

- a. a plurality of anchor plates embedded in the concrete floor and individually surrounding each opening, each anchor plate being substantially planar and having an edge projecting into its associated opening,
- b. a plurality of anchor members individually secured to each jack, each anchor member having a coarse pitch thread configured to fit into and mate with each opening and to engage a projecting anchor plate by turning the jack.

2. An apparatus according to claim 1, in which the thread at the lower end of the anchor member is a few turns.

3. An apparatus according to claim 2, in which the thread is a trapezoidal thread.

4. An apparatus according to claim 1, in which the anchor plate has a central hole, whereby the rim of the hole serves as a projection for the entry of the thread.

5. An apparatus according to claim 4, in which the rim of the hole of the anchor plate is provided with at least one radial slot and is shaped as a single turn screw thread by shaping the edge at both sides of the central plane of the anchoring plate.

15 6. An apparatus according to claim 5, in which the anchor member has a cylindrical guide above its threaded portion which fits into a correspondingly dimensioned cylindrical portion of the floor opening.

20 7. An apparatus according to claim 1, in which the area of the opening directed towards the inside of the garage is provided with a funnel-shaped, conical extension.

25 8. An apparatus according to claim 7, in which the anchor member has a widened conical portion which in the mounted stage engages the conical extension of the floor opening.

9. An apparatus according to claim 8, in which the conical portion is above the cylindrical guide.

10. An apparatus according to claim 9 wherein the 30 dimensions of the widened portion of the anchor member, the conical extension of the floor opening and the anchoring projections of the anchor plate are matched with the dimensions of the opening in such a way that with the jack in the mounted state, the widened portion 35 engages under tension with the contact surfaces of the floor due to the axial movement resulting from the turning of the jack.

11. An apparatus according to claim 1 wherein the anchoring member comprises a thread detachably 40 mounted on the lower end of the jack, a cylindrical guide disposed above said coarse pitch thread and a conical portion above the cylindrical guide.
